UNITED STATES PATENT OFFICE.

JAMES JESSEN, OF MINNEAPOLIS, MINNESOTA.

AUTOMATIC HEAT-CONTROLLER.

No. 841,978.

Specification of Letters Patent.

Patented Jan. 22, 1907.

Application filed November 22, 1904. Serial No. 233,822.

To all whom it may concern:

Be it known that I, JAMES JESSEN, of Minneapolis, county of Hennepin, State of Minnesota, have invented certain new and useful

5 Improvements in Automatic Heat-Controllers, of which the following is a specification.

My invention relates particularly to heat-controllers for pasteurizing and other fluid-treating machines.

10 The object I have in view is to provide means whereby the fluid treated in such machines may be automatically discharged from the machine at a constant predetermined temperature independent of varying steam or fluid supply; further, to provide a device or instrument which may be attached to any machine or installed separate and which will be extremely sensitive, accurate, inexpensive, and easily detachable for the 15 purpose of cleaning the parts exposed to the fluids.

With these objects in view I employ no chemicals, fluids, or anything that is unreliable and will frequently need replacing, but 20 confine myself to simple mechanical constructions.

The invention consists in general of means for exposing the heated fluid directly to the solid surface of two columns of different 25 linear expansive quality and applying this difference in expansion and contraction of the columns to act through suitable co-operating parts directly upon either the heat-supply valve or the inlet-valve for the fluid to be heated, or both.

In most machines the control of the heat-supplying medium alone is sufficient to keep the fluid heated or treated at the desired uniform temperature.

40 Further, I provide means whereby the least perceptible change in temperature in the fluid discharged from the machine will simultaneously take effect on the supply-valves of either the heated or the heating medium and correct the change, while at the same time its range will be great enough to cover all the variations in both the heated or heating mediums supply within the scope of ordinary practice and keep the temperature 45 of the fluid steady at the degree of heat to which the instrument has been set.

My invention consists more specifically in certain constructions and combinations, as set forth in the annexed specification and 50 more particularly pointed out in the claims,

taken in connection with the accompanying drawings, in which—

Figure 1 is a partial end view of a pasteurizer having my device attached thereto. Fig. 2 is a vertical section on the line $x-x$ of Fig. 1. Fig. 3 is a similar section on the line $z-z$ of Fig. 2. Fig. 4 is a section on the line $m-m$ of Fig. 2. Fig. 5 is a vertical section on the line $p-p$ of Fig. 3 on a larger scale. Fig. 6 is a section on the line $y-y$ of Fig. 5. Fig. 7 is a horizontal section on the line $n-n$ of Fig. 3. Fig. 8 is a similar section on the line $k-k$ of Fig. 3. Fig. 9 is a modified form of instrument, showing it as also embodying a temperature-indicator. Fig. 10 is a section on the line $r-r$ of Fig. 9. Fig. 11 shows a preferred form of valve-controlling mechanism. Fig. 12 shows means for also controlling the fluid-supply in connection with the steam-supply. Fig. 13 is a modified form of the valve-controlling mechanism. Fig. 14 shows the instrument as a combined heat indicator and controller applied to a fluid-treating machine. Figs. 15 and 16 are details of the adjusting throw device attached to the operating-shaft. Fig. 17 is partially in section, showing the means for supplying fluid to be treated to the apparatus.

In the drawings, 2 represents a pasteurizer or other fluid-heated machine discharging the heated fluid through a pipe 3. Usually in this class of machines a thermometer 4 is inserted in the discharge-pipe whereby the temperature may be read.

5 is the steam-pipe that admits steam to the machine for the purpose of heating the fluid, and 6 is a hand-operated valve by which the steam may be shut off when the machine is not in use.

A suitable bracket 8, the form of which may vary for different classes of machines, is secured to the pasteurizer 2 and supports the casing 9 of the instrument.

A hollow column or pipe 10, preferably of steel or other material of inferior expansive power, is secured by a suitable detachable coupling 11 to the discharge-pipe 3. A similar coupling 12 connects the pipe 10 to a pipe 13, leading away from the machine.

Referring to Figs. 2 and 3, the pipe 10 is shown detachably secured to an extension of the casing 9 by a swinging clamp 14, provided with a thumb-screw 15. Dowel-pins 16 are arranged between the upper part 17 of the pipe 10 and the casing 9 and serve to al-

ways keep the parts in alinement. A spindle 20 is arranged in bearings in the pipe 10 and is provided within the same with a recessed offset 21.

5 A hollow column 22, preferably of aluminium or other material of superior heat conducting and expansive power, is arranged centrally within the pipe 10 and is supported at its lower end by a detachable pin 23, that 10 passes through the pipe 10. The upper end of the column 22 is edged or pointed and engages the recessed offset 21 of the spindle 20. Lugs 25 serve to guide the column 22 to a central position when it is inserted in the 15 pipe 10. The spindle 20 has, preferably, closed bearings 26 at one side of the pipe 10 and at the other side it passes through the wall of the pipe and is provided on the outside with an annular shoulder or seat 27, that 20 is adapted to make a tight joint with a similar seat on the pipe 10. (See Figs. 2 and 8.)

For convenience I prefer to arrange a lead gasket 28 between the two seats and provide an adjustable screw 29 in the casing 9, by 25 means of which the spindle 20 is adjusted and held against the gasket 28.

A screw 31 keeps the spindle 20 in place when the pipe 10 is removed from the casing 9. A tailpiece 32 projects downward from 30 the spindle 20 within the casing 9 and engages an arm 34 by means of an adjusting thumb-screw 35. (See Fig. 4.) The arm 34 is supported on the stem of the screw 29 and has a lug 36 engaging the thumb-screw 35, 35 by which the parts may be adjusted to control the fluids to any desired temperature, as hereinafter described. The arm 34 extends to the lower part of the casing 9, where it engages the short end of a bell-crank lever 37, 40 that is pivoted to the casing 9 at 38. On the outer end of the lever 37 rests the vertically-moving controller-bar 40, the position of which gages the admission of the heated or heating fluids to the machine. This bar may 45 take several forms, the essential feature of which is a surface inclined to the plane of the movement of the bar induced by the lever 37. This inclined surface may be a part of the lever 37, as shown in Fig. 13. I have here 50 shown it in the form of an inclined slot 41, having walls 41', in which is arranged a beveled lug 42, that is oscillated on a plane at right angles to the movement of the bar 40. The lug 42, is somewhat narrower than the 55 slot 41 and its throw is adjusted so that it will alternately engage the opposite walls 41' of the slot 41 with a free interval. The controller-bar 40 has connections to the controlling steam-valve 43.

60 While I prefer the connections shown in Fig. 11 as simpler, I will now describe Fig. 4, Fig. 5, and Fig. 6. The controller-bar is provided with longitudinal guide-slots 45, into which the guide-blocks 46 and 47 project. The block 46 is pivoted upon an arm 48,

that rocks freely upon a pin 49, provided in the casing 9, while the block 47 is pivoted upon a stationary pin 50. The arm 48 extends through the casing 9 and is provided with a slot 52 at its outer end. A pin or arm 53 engages this slot and is connected to the stem 54 of the steam-controlling valve 43. This valve is preferably of the disk type, although other types of valves may be used. It is provided with openings 55 in a valve-disk 56, that are adapted to register with similar openings 57 in the valve-seat when steam is admitted and with the solid part of the valve-seat when steam is cut off. The valve 43 has connected with it the admission-pipe 57 and the discharge-pipe 58 and is provided with the stuffing-box 59.

Returning to the controller-bar 40, the lug 42, operating thereon, is carried by one arm of a bell-crank lever 60, that has the same 80 pivotal center as the block 48. A link 61 connects the other arm of the lever to a crank-pin 62. This pin is adjustably secured to a shaft 63 by means of adjusting-screws 64, bearing against a lug 65, that projects into a recess 66 in the head of the shaft 63. (See Figs. 2, 15, and 16.) The lug 65 and pin 62 are preferably cast integral with a plate 67, that is connected to the shaft by a screw 68. The shaft 63 has bearings in the 95 casing 9 and is provided with a driving-pulley 70. By reference to Fig. 4 it will be seen that as the shaft 63 revolves the crank-pin 62 will give an oscillating movement to the beveled lug 42.

In practice the movement of the lug is adjusted to compensate for all play in the slots 41 and 48 and the intervening joints between the valve 43, so as to impart a barely-perceptible impulse of the valve at each stroke. It 100 is obvious that under these conditions the slightest displacement of the vertical controller-bar 40 up or down will by the action of the lug 42 on its inclined walls 41' deflect the controller-bar and partially rotate the steam-valve to admit or cut off steam, as required. To compensate for heavy irregularities in the steam-pressure or in the flow of the fluid through the machine, the inclined section of the bar 40 and connections to the 110 steam-valve are proportioned so that a maximum displacement of the controller-bar in a certain direction will throw the steam-valve from closed to full open and conversely. The displacement of the controller-bar is caused by the varying temperature of the fluid passing through the pipe 10 and hollow column 22.

By referring to Figs. 2, 3, and 4 it will be 115 seen that the weight of the controller-bar 40, resting on the bell-crank lever 37, exerts a tension on the column 22, acting through the arm 34 and armed spindle 20. A greater expansion of the column 22 than of the pipe 10 thus forces the arm 34 outward, which, acting 120

on the lever 37, raises the controller-bar 40. Conversely, an excessive contraction of the column 22 allows the bar 40 to drop.

The coöperating parts of the instrument 5 are proportioned so that a change of position of the bar 40 from one extreme of the incline to the other involves a variation of a few degrees, but induces an extreme valve-action. By reason of the smooth inclined surface of 10 the inclined walls 41' and the direct fluid contact with the expansion-column no change can take place in the discharged fluid without at once deflecting the bar 40 and effecting a partial operation of the valves. 15 This renders the instrument extremely sensitive and accurate.

It is evident from the above that the instrument may be adjusted to control the temperature of the discharged fluid within 20 the whole range of the combined, original heat of the two mediums entering the machine, less the heat lost by radiation and condensation by changing the position of the inclined plane bar 40 independent of the expansion-columns 22 and 10. When, for example, the parts are proportioned so that at a temperature of 160° Fahrenheit the relative expansion of the columns 10 and 22 is such that the inclined plane is exactly 25 central to the oscillating lug 40, it follows that if the plane is now raised or lowered independently of the columns 10 and 22 the instrument will adjust itself to a higher or lower temperature, respectively. The adjustment may be interposed at any point between the columns and the bar 40; but for the sake of simplicity I prefer to arrange the adjusting connection between the arm 34 and tailpiece 32.

40 In Fig. 11 I have shown a preferred construction of the connections between the operating crank-shaft 63, bar 40, and valve 43. The link 61 is here shown connected directly to a vertical link 71, that is connected to the 45 valve-arm 53 and is provided with the lug 42. The bar 40 instead of being guided by the slots 48 is guided between parallel walls 72 and 73 of the casing 9 and is provided with guiding-ribs 74. The inclined slot 41 is continuous with the parallel slots 48, and thus admits of a greater movement of the bar. In the position shown the steam-valve will be closed; but as the temperature drops the bar will drop until the inclined plane of the slot 41 comes in engagement with the lug 42 upon the oscillating link 71, when the movement of the lower part of the link will be temporarily arrested and the motion will be transmitted to the upper part, which then will open the 55 steam-valve, after which the lug 42 will be oscillating between the inclined walls 41' of the slot 41 ready to throw the valve in either direction with a change of temperature. In this case link 71 only, and not the bar 40, is deflected horizontally to move the valve 43;

but in Figs. 3 and 4 the bar 40 itself is deflected around the pivot 47 to move the arm 48, which in turn moves the valve 53.

In Fig. 12, 75 represents the inlet-pipe for the fluid to be treated in the machine. A 70 valve or damper 76, adapted to interrupt the flow of the fluid into the machine, is arranged within the pipe 75. An arm 77 is secured to the stem of this valve and is connected to the steam-valve 43 by a link 78. In this way 75 when more steam is turned on the flow of fluid into the machine is simultaneously reduced. This is principally of use in pasteurizing-machines of poor heating capacity or where abnormal changes of steam-pressure or fluid- 80 supply occur.

In attaching the instrument to machines not provided with a thermometer I prefer to make it self-indicating, as shown in Figs. 9 and 10. The bell-crank 37 then takes the 85 form of a sector or disk 80, and its connection to the arm 34 is preferably by means of a pinion 81 and rack 82 or an equivalent to permit a wider range of movements.

A graduated scale or dial 82' is arranged on 90 the face of the disk 80, and I also provide means whereby the instrument may be adjusted to the desired temperature by moving a pointer over the dial to the desired degree, after which it will adjust itself and control the 95 temperature at that degree. An arm 84, having a sleeve 85 extending outside the casing 9 and being there provided with an operating-knob 86, is journaled on the pin 38. The sleeve 85 turns on the hub 87 of the disk 80 100 between a shoulder 88 and a check-nut 89, by which latter the arm 84 is secured to the disk 80. The arm 84 has a lug 89 projecting over the periphery of the disk 80, and a flexible strap 90 is secured to the lug 89 and, resting 105 on the periphery of the disk 80, is fastened to the lower end of the controller-bar 40. A pointer 91 is connected to the arm 84 and is arranged to coincide with the central part of the inclined slot 41 of the bar 40. A stationary pointer 93 (see Fig. 9 and Fig. 14) is provided on the casing 9, by which the dial 82 may be adjusted to indicate the correct temperature by means of the screw 94 at the top of the instrument. 115

A glass pane 95 is provided in the front wall of the casing 9, through which the indicator may be read. The pulley 70 is constantly driven at a slow speed during the operation of the machine and may be driven by 120 a belt from any convenient source.

When the pasteurizing is done, the couplings 11 and 12 are unscrewed and the clamp 14 released, after which the pipes may be removed from the instrument and by removing 125 the pin 23 the inner column 22 may be removed for cleaning.

It is obvious that various modifications may be made without departing from the principle of the invention. I do not, there- 130

fore, wish to confine myself strictly to the construction shown.

While I have shown the outflow-pipe 10 in a vertical position to adapt it to a certain class of machines, for various fluid-treating machines it may be necessary to place the outflow-pipe 10 in a horizontal position and arrange the parts accordingly.

I claim as my invention—

1. The combination, with a suitable receptacle, means for supplying thereto a fluid, to be tempered, and means for supplying thereto a tempering fluid, of a valve controlling the admission of said tempering fluid, an eccentric, connections between the said eccentric and the said valve, and means controlled by the temperature of the fluid in said receptacle for causing said eccentric to move the valve to an extent proportioned to the degree said temperature varies from the temperature desired.

2. The combination, with a pasteurizer and means for supplying a heating fluid thereto, of a valve controlling the admission of said heating fluid, means for admitting a fluid to be treated, a controller-bar provided with a slot having inclined walls, a connection between said controller-bar and said valve, a thermostatic column acted upon by the temperature of the fluid being treated, a connection between the thermostatic column and the controller-bar, and an oscillating lug engaging the slot in the controller-bar.

3. The combination, with a fluid-tempering receptacle, means for supplying a tempering fluid thereto and means for supplying thereto a fluid to be treated, of a valve controlling the flow of the fluid under treatment, a controller provided with inclined planes, an oscillating part engaging the said planes, connections between the said oscillating part and the said valve, a thermostatic column acted upon by the temperature of the fluid under treatment and connections between the said column and the said controller.

4. The combination, with a pasteurizer and means for supplying a heating fluid thereto, of a valve controlling the admission of said heating fluid, a power-operated oscillating device for moving said valve, a connection between the said valve and the said oscillating device, and a thermostatic column controlling the connection between said valve and said device.

5. The combination, with a pasteurizer and means for supplying a heating fluid thereto, of a valve controlling the admission of said heating fluid, power-operated mechanism for moving said valve, an inclined controller-bar forming a connection between said mechanism and said valve, and a thermostatic column governing the position of said controller-bar.

6. The combination, with a pasteurizer, and means for supplying a heating fluid

thereto, of a valve controlling the admission of said heating fluid, a controller-bar provided with an inclined slot connected with said valve, a power-operated oscillating lug engaging said slot, and a thermostatic column governing the position of said bar.

7. The combination, with a suitable receptacle and means for supplying a tempering fluid and a fluid to be tempered to the said receptacle of valves controlling the flow of fluids within the said receptacle, a power-driven oscillating device and means controlled by the temperature of the contents of said receptacle to cause the said oscillating device to move the said valves in either direction to an extent proportional to the degree the temperature of said contents varies from the temperature desired.

8. The combination, with a fluid-tempering receptacle and means for supplying thereto a tempering fluid and a fluid to be tempered, of a thermostatic column acted upon by the tempered fluid, a valve controlling the flow of fluid, within the receptacle, an oscillating device, a controller-cam acted upon by the said device, means controlled by the thermostatic column and cooperating with the said oscillating device and the said cam to gradually move the valve in either direction and means for adjusting the extent of the movement of the said valve.

9. The combination with a pasteurizer or other fluid-treating machine and means for supplying thereto a tempering fluid, of columns of unequal expansive power, exposed to the tempered fluid, a valve for controlling the admission of the fluid to be tempered, means for supplying a fluid to be treated, an inclined plane, a moving body adapted to come in contact with the said plane, connections between the said columns and the said inclined plane, and between the said moving body and the said admission-valve whereby the difference in expansion and contraction of the said columns operates to vary the relative positions of the said moving body and the said inclined plane and to move the said admission-valve.

10. The combination, with a pasteurizer or other fluid-treating machine and means for supplying thereto a tempering fluid and means for supplying a fluid to be treated, of columns of unequal expansive power, means for exposing the said columns to the heating or cooling influences of the treated fluid, an inclined plane, means for moving the said plane by the said columns, a moving body adapted to come in contact with the said plane, valves to control the admission of the fluids and connections between the said inclined plane, the said moving body and the said admission-valves whereby the said valves are operated when the inclined plane is moved.

11. The combination, with a fluid-temper-

- ing receptacle and means for supplying thereto a tempering fluid and a fluid to be tempered, of a thermostatic column acted upon by the tempered fluid, a valve controlling the flow of the fluid, within the receptacle, an oscillating device, means controlled by the thermostatic column and coöperating with the said oscillating device and the said cam to gradually move the valve in either direction and an indicator adjustably connected to said cam. 12. The combination, with a fluid-tempering receptacle and means for supplying thereto a tempering fluid and means for supplying a fluid to be treated, of a thermostatic column acted upon by the tempered fluid, a valve controlling the flow of the tempering fluid within the receptacle, a driving-wheel, an oscillating device connected to the said wheel, a controller-cam provided with inclined and parallel planes and acted upon by the said oscillating device, connections between the said device and the said valve, and connections between the said controller-cam and the thermostatic column. 13. The combination, with a fluid-tempering receptacle and means for supplying a tempering fluid and a fluid to be tempered, of a thermostatic column acted upon by the tempered fluid, a valve controlling the flow of the fluid within the receptacle, a driving-wheel, an oscillating device connected to the said wheel, and to the said valve, a cam controlled by the thermostatic column and provided with inclined and parallel planes, said oscillating device acting upon the said planes, an indicator, adjustable connections of the said indicator to the said cam and an adjusting-pointer for adjusting the temperature of the contents of the receptacle to the degree desired. 14. The combination, with a fluid-tempering receptacle and means for supplying thereto a tempering fluid and a fluid to be tempered, of a thermostatic column acted upon by the tempered fluid, a controlling-cam provided with inclined and parallel planes, adjustable connections between the said cam and the said thermostatic column, a power-driven oscillating device acting upon the said cam, a valve, and connections between the said valve and the said oscillating device. 15. In a heat-controller, the combination with a pipe 10, of a column 22, having a different coefficient of expansion, supported within the pipe 10 by means of the pin 23 and cranked spindle 21, bearings in the pipe 10 for the spindle 21, an annular shoulder 27 provided on the said spindle and seated against the pipe 10, an arm 32 extending from the spindle 21 and engaging the adjusting-screw 35 of the lever 34, a cam 41', an oscillating lug 42, a valve 43 and connections between the said valve, the said cam and the said lever. 16. In witness whereof I have hereunto set my hand this 9th day of November, 1904.

JAMES JESSEN.
